US0D1038413S

(12) **United States Design Patent** (10) **Patent No.:** **US D1,038,413 S**
(45) **Date of Patent:** **** Aug. 6, 2024**

(54) **TANK**

(71) Applicant: **Renu Therapy, LLC**, Costa Mesa, CA (US)

(72) Inventor: **Bill Bachand**, Santa Ana, CA (US)

(73) Assignee: **Renu Therapy, LLC**, Costa Mesa, CA (US)

(**) Term: **15 Years**

(21) Appl. No.: **29/933,630**

(22) Filed: **Mar. 20, 2024**

Related U.S. Application Data

(63) Continuation of application No. 29/914,341, filed on Oct. 16, 2023, which is a continuation of application No. 29/870,181, filed on Jan. 18, 2023, now abandoned, which is a continuation of application No. 29/811,925, filed on Oct. 18, 2021, now Pat. No. Des. 983,983, which is a continuation of application No. 29/757,138, filed on Nov. 3, 2020, now Pat. No. Des. 936,234.

(57) **CLAIM**

The ornamental design for a tank, as shown and described.

DESCRIPTION

FIG. 1 is a front, right-side perspective view of a tank showing an embodiment of my design with a lid removed; FIG. 2 is a rear, left-side perspective view thereof with the lid removed;

FIG. 3 is a front, right-side perspective view thereof;

FIG. 4 is a top plan view thereof;

FIG. 5 is a bottom plan view thereof;

FIG. 6 is a right-side elevation view thereof;

FIG. 7 is a left-side elevation view thereof;

FIG. 8 is a front elevation view thereof; and,

FIG. 9 is a rear elevation view thereof.

The broken lines shown in the drawings represent portions of the tank that form no part of the claimed design.

1 Claim, 9 Drawing Sheets
